UNITED STATES PATENT OFFICE.

RICHARD H. WELLES, OF KENOSHA, WISCONSIN, ASSIGNOR TO THE BADGER BRASS MANUFACTURING COMPANY, OF KENOSHA, WISCONSIN, A CORPORATION OF WISCONSIN.

DESIGN FOR A HEADLIGHT.

41,397.

Specification for Design. Patented May 23, 1911.

Application filed May 4, 1910. Serial No. 559,419. Term of patent 7 years.

To all whom it may concern:

Be it known that I, RICHARD H. WELLES, a citizen of the United States, residing in the city of Kenosha, county of Kenosha, and State of Wisconsin, have invented a new, original, and ornamental Design for Headlights, of which the following is a specification, reference being had to the accompanying drawings, forming a part thereof.

In the drawings Figure 1 is a side elevation of my new design and Fig. 2 a rear end elevation of the same.

The salient or distinguishing features of the design may be briefly described as follows: A generally cylindrical barrel or main body portion 1 having a substantially smooth exterior surface is provided at its rear end with a reduced convex closure portion 2 and at its forward end with a flaring front portion 3 to which is secured the door 4 having a glass 5. To the base of the lamp is secured the oil font 6 and at the rear of the lamp is fixed a plug 7 to receive a pair of

electric wires 8, the lamp being intended for two kinds of illumination. Surmounting the main body is a tier of top ventilators 9, 9 decreasing in radial width toward the top of the tier. The main body of the lamp as well as a portion of the font and top ventilator is preferably of dark color, as shown in the drawings. The lamp is also provided with a curved handle which extends over the top of the ventilator and is secured to opposite sides of the lamp as shown at 11.

The design as a whole is such as to provide an exterior surface substantially free from ribs, beads or other projections or sharp angles, this feature giving the lamp a decided novel and distinctive appearance.

I claim:

The ornamental design for a headlight as shown and described.

RICHARD H. WELLES.
